GOTTLOB BURKHARDT, OF HERRENALB, GERMANY, ASSIGNOR TO JULIUS M. BURKHARDT, JOHN FRED. BURKHARDT, AND LANCE NICHOLSON, ALL OF BUFFALO, NEW YORK

WATER-TUBE BOILER

Application filed January 15, 1926, Serial No. 81,552, and in Germany January 16, 1925.

This invention has reference to improvements in water tube boilers, and it refers in particular to that class of the boilers referred to generally known as sectional or chambered water tube boilers adapted for use with high pressures, and it is intended to devise means of overcoming and eliminating the difficulties which result from unequal bending and differences of strain in the several tubular elements and in their connecting means with the chambers and with the upper and lower drums of the boiler. In the chambered water tube boilers or sectional boilers with clusters of straight water tubes arranged between parallel sections, chambers or compartments, as heretofore constructed, great difficulties are experienced with the high efficiencies and high pressures now generally employed in view of the unequal heating and unequal extension in the several tubes and the consequent excessive high pressure in the axial direction of the tubes exposed to higher temperatures, while other tubes in the vicinity thereof, but with lower temperature are exposed to a very high tensional strain in the axial direction. As a result thereof, either the tubes become loosened and displaced at their points of connection with the chambers or compartments, or the tubes which are heated to a relatively higher temperature are subject to a very serious bending strain by the influence of the excessive axial pressure. This difficulty is particularly noticeable in that kind of well known sectional boilers in which the vertically disposed clusters of ascending and descending tubes are connected at their lower ends with one and the same chamber, while their upper ends are connected to separate chambers which, if required, may be joined to the upper boiler or drum of the system. While with moderate operating pressures and moderate interior temperatures these difficulties, though noticeable, are not particularly serious and very dangerous, yet with high pressures the rigidity of connection of the clusters of tubes causes a very serious danger for the safety of the boiler. In order to overcome these difficulties, sectional water tube boilers have been suggested in which curved water tubes, some of which with their straight terminal portions arranged in axial alinement, are disposed between parallel chambers or compartments, but with this construction of boilers there is the difficulty that the water tubes, though somewhat resilient, in view of their relatively deep and irregular curvature, cannot be inserted in the apertures of the chambers opposite their ends, nor withdrawn therefrom, and that it is not possible to properly clean such tubes in the manner readily applicable in the case of the ordinary straight water tubes between parallel chambers or boilers. Now, in view thereof, it is one of the important objects of my invention to dispose the water tubes between upper and lower boilers, chambers or compartments in parallel relation to each other in such a manner that every tube, in view of its peculiar bend, is free to extend and contract, without exerting any excessive tensional strain on the neighboring tubes, and is yet adapted to be readily inserted through the connecting holes in the boilers or chambers opposite the tube ends and to be withdrawn therefrom, while, at the same time, presenting no difficulty to the required interior cleaning of the tubes. This object is accomplished in my invention, broadly speaking, by so arranging the curvature of the water tubes that they are bent in conformity with the line of bending stress of a hypothetical rod or beam secured at both of its ends and guided in the original straight axis of the tube, when under compression, the resulting curvature being sufficiently gentle or of sufficiently small degree as to allow of the tubes being withdrawn through the connecting openings in the chambers or boilers opposite the ends of the tubes while at the same time permitting the tubes to contract and expand and flex laterally as required under service temperatures and pressures.

While with this arrangement of water tubes in sectional boilers chambers may be used in combination with one or more upper boilers or drums, it becomes possible to so combine the flexible water tubes with parallel and spacedly arranged chambers in chambered

water tube boilers with vertically disposed clusters of ascending and descending tubes, that the adjacent chambers may be directly connected to each other, without the intermediary of the upper boiler, while with the previous constructions the chambers, on account of the unequal expansion of the two groups of tubes or pipes, had to be kept separate from each other, and by this means it becomes possible, in accordance with my invention, to provide an uninterrupted continuous circulation of the water, while the generated steam and the replenishing water corresponding thereto may be withdrawn from and respectively introduced into the main circulating current in a separate cycle. The vertical tube boilers with upper drum and lower chambers connecting the bottom ends of the ascending and descending tubes, if modified according to my invention by the combination with water tubes bent in accordance with the line of bending stress, therefore, become adapted to be used with high pressures and for high efficiencies by either providing the upper drum in the ordinary manner with the walls of the tubes in parallel stepwise relation and in parallel relation to the chambers, or by making use of an even cylindrical shell. In the latter case, the pipe holes in the upper drum are so arranged that their centres are in the axial alinement with the lower straight ends of the pipes or tubes, so as to admit of a lateral twist of the water tube on said straight axis.

Further advantages of the invention will appear from the specification and drawings and from the description of a preferred embodiment of the principles of the invention shown in the drawing in which Fig. 1 is a section of a furnace with a sectional vertical tube boiler, having a group of ascending and a group of descending tubes with superposed upper boilers. Fig. 2 is a front view of the cluster of water tubes.

As appears from Fig. 1, the chambers for the ascending group of tubes 1 and for the descending group 2 are arranged parallel to each other and the upper chambers 3, as well as the lower chambers 4, are connected by comparatively broad tubes to each other; they may, of course, also be made in one piece or integral with each other. The main circulating current rises in the ascending tubes 1, passes through the chambers 3 and the tube connection between the same at the highest point of which the steam bubbles are conducted through the steam pipes 5, 6, 7, 8 into the upper boilers 11, 12, while the replenishing feed water is introduced into the main circulating current by the pipes 9 and 10; thence the water current flows through the descending tubes 2 and into the lower chambers 4 and then back again into the group of ascending tubes. The upper cham-

bers 3 may be connected to one or a plurality of upper boilers or drums 11, 12 through which the shunt circulation referred to is effected.

In order to provide for each separate tube or pipe being inserted vertically or approximately vertically in the shell of the chambers, so as to be connected thereto by the ordinary rolling process, while, at the same time, admitting for an expansion or contraction of the tubes, the ends of each tube are preferably disposed in axial alinement with each other and the curvature of the tubes is so arranged that it will correspond to the line of bending stress of an originally straight bar under load, the bend being comparatively gentle and arranged so as to merge gradually into the terminal portions of the tubes. In view of this construction, the tubes can be easily withdrawn through the connecting holes of the chambers opposite the pipe ends and may be cleaned through these holes. The bend of these water tubes is, however, sufficiently large as to allow of each tube being adapted to expand and respectively become shortened as a result of its increase or reduction of length, without thereby exerting any inadmissibly large pressure or tensile strain on the walls of the chambers.

The water tubes arranged and bent in the manner described (a and b, Figs. 1 and 2), in view of their ends being disposed in axial alinement, present the further important advantage that they may be turned laterally to the left or right and alternately, if desired, on one and the same axis, so that by this means the well known heating process may be carried out with tubes constructed according to my invention, in which process the gas currents are compelled to intersect each other twice at least, so as to produce very thorough whirling around and intermingling of the heating gases and a very substantial increase of efficiency and superior transmission of heat.

While the invention has been shown and described herein with reference to a preferred embodiment thereof, it should be understood that its principles may find expression in other embodiments and modifications, so as to better adapt the invention to varying conditions of application and without deviating from its scope and spirit, as particularly defined in the appended claim.

In this connection it may be pointed out that the upper chambers 3 may be replaced directly by the upper boilers or by one of them which are preferably arranged in parallel relation to the lower chambers. The centres of the connecting holes for the insertion of the tubes are preferably in axial alinement with the lower terminal parts of the tubes.

I claim:—

In an upright water tube boiler, a circulatory system comprising highly and less highly heated sets of ascending and descending curved water tubes, parallelly arranged headers directly connecting the upper and the lower ends of the tubes to each other, water and steam containing means above the upper headers, one of said upper headers being arranged below the level of the other, tubes connecting the headers, tubes directly connecting the water and steam containing means with the upper header arranged at the higher level, and tubes connecting the water and steam containing means with the tubes connecting the upper headers at a point between said headers.

In testimony whereof I affix my signature.
GOTTLOB BURKHARDT.
